Cecil H. Lawrence, Attleboro, Mass., assignor to
Evans Case Company, a corporation of Massachusetts

Application September 12, 1935, Serial No. 58,538

Term of patent 3½ years

To all whom it may concern:

Be it known that I, Cecil H. Lawrence, a citizen of the United States, residing at Attleboro, county of Bristol, and State of Massachusetts, have invented a new, original, and ornamental Design for Hand Mirrors or the like, of which the following is a specification, reference being had to the accompanying drawing, forming a part thereof.

Fig. 2 is a side view of the same.

I claim:

The ornamental design for a hand mirror or the like as shown.

CECIL H. LAWRENCE.
